UNITED STATES PATENT OFFICE.

JOHN A. MACDOSELL, OF ST. LOUIS, MISSOURI.

METHOD AND STRUCTURE OF BOILER BAFFLES.

Application filed May 26, 1926. Serial No. 111,697.

This invention relates to improvements in the construction of baffle or fire walls for water tube boilers.

The primary object of the invention is to show a method of constructing a baffle wall which in its installation includes closely fitting and fire-proof sealing bonds for the joints between the wall and the enclosed tubes, whereby so long as the structure remains undisturbed, heat leakage or short circuiting of the heat currents through those joints will be prevented; the said bonds, however, being relatively weaker and more friable than the remaining or adjacent portions of the wall, to the end that when it becomes necessary to remove the said tubes for replacement or repair, this may be readily done by merely twisting and pulling the tubes, whereby the said bonds are ruptured without rupturing the wall proper, after which the tubes may be withdrawn.

A further object is to set forth a practical embodiment of the method referred to, in the form of an actual baffle wall built in accord with the said method.

In the drawing

Figure 1 represents a cross section through a portion of a water tube boiler and through the corresponding portion of a baffle wall constructed therein in accordance with this invention;

Figure 2 is a longitudinal section through a portion of the boiler and wall;

Figure 3 is a detail of a baffle wall block or tile of a form well adapted to the exemplification of this invention.

In carrying out this invention I provide baffle tiles 1 made of fire clay or the like and formed with oppositely disposed, arcuate or semi-circular cut-outs 2 adapted to engage and embrace at opposite side the boiler tubes 3. The arcuate margins of the cut-outs 2 are tapered or beveled to comparatively fine or thin and frangible edges, as shown at 4, and the provision of these tapered or beveled edges upon the said tile, constitutes one of the essential features of my invention. The other two opposite margins of the tiles may be also beveled off at opposite faces of the tiles and to comparatively blunt edges, as shown at 5 and 6 to form laps, as described in the co-pending application of the present applicant.

In constructing a baffle wall 7, I first coat the tubes 3, in the plane of the proposed wall, with substantial coating or bonds 8

of lime, mortar, or any other form of mortar which will be plastic in application, siccative after the application, and incombustile and friable after the same has set. 60 These sealing bonds are laid on to the thickness of approximately one-eighth of an inch over the entire circumferences of the tubes, and for a length corresponding to the thickness of the proposed wall, exclusive of the 65 thickness of the tiles 1 to be used at each side of that wall.

I next erect spaced wall shells 9 at each side of the space defined by the coatings or bonds 8, and at the ends of those coatings, 70 by filling in with the tile 1 between the tubes 3. For this purpose the cut-outs 2 are placed in lateral engagement with adjacent ones of the tubes, with the upper tiles successively overlapping the lower ones, and 75 with the lower laps 10 directed inwardly, as shown in Figure 2. In this operation the fine edges 4 of the cut-outs are turned inwardly and are crowded well up against the ends of the coatings or bonds 8 imposed 80 upon the tube 3 as aforesaid. In building up the said shells, the tiles should of course be accurately aligned with each other, in transverse parallel planes relative to the boiler tubes. After the coatings 8 have 85 dried, "set" or hardened sufficiently to bear the weight or pressure without injury to the coatings, any desired viscous or plastic, siccative and incombustible filler, as for instance, plastic fire clay as represented at 11, 90 may be poured in at the top of the structure and allowed to flow down and fill the spaces between the two shells. Owing to the inwardly overlapped relation of the tiles, the plastic filler will not work out between them. It is essential that the mortar used in providing the coatings or bonds 8 should be of some friable or crumbly, as well as incombustible material, such as lime, 95 so that after the coatings harden, they will 100 effectually seal the joints between the tubes and wall against the short circuiting of heat currents, but may be nevertheless easily ruptured and broken whenever it may be desired to remove any of the tubes 3. 105

When this event occurs and it is desired to remove any one of the tubes for repair or replacement, this may be readily accomplished by turning, twisting and pulling upon the tube, thereby breaking and 110 crumbling the encircling edges 4 of the tiles, and also the friable bond 8 between the tube

and the wall proper, after which the tube may be easily withdrawn. When the tube is replaced, the joint between the tube and wall may be again sealed with a similar lime 5 mortar or paste. The two essential features of this method, therefore, consist in the provision of spaced baffle wall shells which contact with the water tubes through their tapered, beveled or reduced and relatively frangible edges; and friable and incombustible bonds interposed between the surfaces of the tubes within the said shells and the wall proper which is filled in between the said shells.

15 And while I have herein set forth and described my method with a certain particularity of structural detail, it is understood that I may vary the said details as may seem practicable or expedient, without departing 20 from the spirit of my invention, as defined in the appended claims.

I claim:

1. The method of constructing a baffle wall for a water tube boiler, consisting in first coating the tubes in the plane of the proposed wall and for lengths approximately equal to the thickness of the wall with sealing bonds of material which will be plastic in the application, siccative after the application and incombustible and friable after the same has set; then erecting spaced wall shells at each side of the space defined by the said bonds, the said shells being provided with tapered and relatively frangible edges at their points of contact with the said tubes; and after the said bonds have set, filling in the spaces between the shells with a plastic, siccative and incombustible material.
2. The method of constructing a baffle wall for a water tube boiler, consisting in coating the tubes in the plane of the proposed wall for lengths approximately equal to the thickness of the wall, with coatings of friable and incombustible material; erecting spaced wall shells at each side of the space defined by the said coatings, the said shells being composed of tiles having semi-circular cut-outs adapted to embrace adjacent water tubes, the margins of the said cut-

outs being reduced to relatively thin and 50 frangible edges adapted to contact with the said tubes; and then filling in the spaces between the shells with some viscous, siccative and incombustible material.

3. In a baffle wall for a water tube boiler, 55 spaced shells for the said wall, the said shells having semi-circular, tapered and relatively frangible edges contacting with the water tubes.

4. In a baffle wall for a water tube boiler, 60 incombustible and friable bonds for the joints between the wall and the boiler tubes.

5. In a baffle wall for a water tube boiler, incombustible and friable bonds for the joints between the wall and the boiler tubes, 65 the said bonds being composed of material which will be plastic for application, siccative after application and incombustible and friable after the same has set.

6. A baffle wall for a water tube boiler, 70 comprising spaced shells arranged transversely of the tubes and contacting with the tubes through reduced and relatively frangible edges; friable and incombustible sealing bonds upon the tubes between the said shells; 75 and a filler interposed between the said shells.

7. In a baffle wall structure for a water tube boiler, spaced wall shells arranged transversely of the tubes and having reduced 80 and relatively frangible edges contacting with the tubes.

8. In a baffle wall structure for a water tube boiler, friable and incombustible sealing bonds interposed at the joints of the 85 tubes and the wall, and separating the tubes from the wall proper.

9. A form of tile for building a baffle wall for a water tube boiler, the same consisting of a flat formation of frangible material, 90 having an arcuate cut-out at one of its margins for engaging one of the water tubes, the said margin at the said cut-out being reduced to a relatively thin edge adapted to contact with the water tube.

In testimony whereof I affix my signature.

JOHN A. MACDOWELL.
